COUPLING SYSTEM FOR LOADING DEVICES
SUCH AS AERIALSPierre Paul Gamet, Paris, France; vested in the
Alien Property CustodianApplication May 9, 1942, Serial No. 442,373
In France May 26, 1941

2 Claims. (Cl. 250—33)

This invention has for its subject-matter improvements in and relating to coupling systems for radio-frequency output devices such as antennae.

The matching over a wide range of wave lengths of a transmission line through a coupling box connected between the said transmission line and the output device or through adjustable inductance coils connected in series in one of the conductors of the said transmission line obliges the operator to make an adjustment for the different operating wave lengths. This adjustment is generally obtained by varying the electric constants of the coupling impedances or the inductance coil connected in series in the transmission line.

These matching or adjusting circuits are expensive and require considerable space.

The present invention has for its object to avoid these disadvantages and to permit of obtaining without different adjustments a convenient matching of the transmission line from the point of view of the supply voltage over a wide range of wave lengths.

On the other hand it is often necessary to vary the voltage which is delivered by the high-frequency generator by the transmission line to any output device. This variation is generally obtained by a modification of the connection of the high-frequency generator with the transmission line as, for instance, by means of adjustable taps on the inductance coil of the oscillatory circuit. Such adjustable taps are of a difficult and delicate construction and do not permit an accurate regulation.

Another object of the invention is to remedy this inconvenience and to provide a device permitting to control the coupling values within certain limits.

The same difficulties are encountered in coupling systems for coupling two radio generators connected in parallel when they are not well matched or balanced.

Still another object of the present invention is to remedy these inconveniences and to provide a device which compensates in a certain measure for the differences in the energy produced by one of the radio generators, these differences being due, for instance, to an accidental variation of the potential of the grid bias.

Improved coupling systems which permit to attain the above mentioned objects present the characteristic features which appear from the following description and more particularly from the appended claims.

Coupling systems according to the present invention are shown in the appended drawing, in which:

Figure 1 is a diagram of the coupling of a high-frequency generator with a transmission line with stationary waves through a fixed resistance.

Figure 2 is a diagram of the coupling of a high-frequency generator with a transmission line with stationary waves through a variable resistance.

Figure 3 is a diagram of the coupling of a transmission line for stationary waves with two high-frequency generators connected in parallel.

The diagram shown in Figure 1 comprises a transmitter station 1 comprising an oscillatory circuit formed of a variable capacity 2 and of an inductor 3; a tap 4 provided on the inductor 3 is connected with a resistance 5 in series with the conductor 6 of a co-axial transmission line 7; the other extremity of this transmission line is connected with the output device 8 (an antenna, for instance).

The operation of this coupling system is as follows:

The oscillating circuit transmits the high-frequency oscillations which it produces to the output device 8 through the medium of the resistance 5 and of the co-axial transmission line 7. The input impedance of the unit formed of the co-axial transmission line 7 and the output device 8 varies as a function of the wave lengths which are produced by the generator 1.

Owing to these variations of the impedance of the transmission line 7 and of the output device 8 as a function of the wave lengths which are transmitted, the high-frequency excitation voltage varies.

For a small input impedance, the high-frequency excitation voltage is moderate and if the tap on the inductor 3 corresponds to an excitation voltage which is higher than the voltage which had been intended, a voltage drop is produced across the terminals of the resistance 5.

Thus, the impedance between the tap 4 and the output device 8 seen from the transmitter side is increased owing to the resistance.

For a high input impedance, the high-frequency excitation voltage is entirely transmitted; indeed, the value of the resistance 5 is negligible with respect to the input impedance of the transmission line.

Thus, the resistance 5 tends to bring the connected impedance seen from the transmitter side to such a value that fixed coupling is possible on the inductor 3.

The transmitter apparatus shown on Figure 2

is similar to that shown in Figure 1, but the fixed resistance 5 is replaced by a variable resistance 9. The latter permits of varying within certain limits the high frequency voltage transmitted by the generator 1 to the output device 8 owing to the voltage drop RI caused by the current flowing through the said resistance. When a loose coupling is desired, the resistance is adjusted to the maximum of its value. On the contrary, when a close coupling is desired, the resistance is adjusted to the minimum of its value. The coupling can take all the intermediary values which are permitted by the variation of the resistance 9 from its minimum to its maximum.

In Figures 1 and 2 the resistances 5 and 9 have been shown at the input of the co-axial transmission line, but they can be located at any point on the transmission line.

The transmitter apparatus shown in Figure 3 comprises two transmitter stations 10 and 11 connected with a common transmission line through the medium of resistances 13 and 14, the resistance 13 connecting the transmitter 10 with the transmission line 12 while the resistance 14 connects the transmitter 11 with the transmission line 12.

In Fig. 3, the station 10 has variable capacity 22, and inductor 23, with tap 24, which correspond respectively to capacity 2, and inductor 3 with tap 4, at station 1 in Fig. 1. Also in Fig. 3, the station 11 has variable capacity 22a, and inductor 23a with variable tap 24a, which correspond respectively to capacity 2, and inductor 3, with tap 4, in Fig. 1.

The operation of the device is as follows:

The current delivered from the transmitters 10 and 11 flows through each of the resistances

13 and 14; if, for any reason owing to an accidental variation of the grid excitation, one of the transmitters produces a larger output, a stronger current flows through the corresponding resistance which dissipates more energy, thus tending to bring to its normal value the energy received by the output device.

The invention is of general applicability and can be applied to all kinds of output devices; it is more particularly advantageous for transmitters for working stations with a wide range of wave lengths, or for transmitting devices which use large bands such as the transmission of images in television.

I claim:

1. In a high-radio-frequency circuit system, a pair of radio-frequency oscillator circuits each comprising an inductance having an adjustable tap, a radio-frequency power consumption unit, a co-axial transmission line having its axial conductor connected to said power consumption unit, and individual connections each comprising a series resistance extending between the end of said axial conductor remote from said consumption unit, and said adjustable taps respectively.

2. In a high-radio-frequency circuit system, a pair of radio-frequency oscillator circuits each comprising an inductance having an adjustable tap, a transmitting antenna unit, a co-axial transmission line having its axial conductor connected to said antenna unit, and individual connections each comprising a series resistance extending between the end of said axial conductor remote from said antenna unit, and said adjustable taps respectively.

PIERRE PAUL GAMET.
